UNITED STATES PATENT OFFICE.

ANKER PETERSEN, OF WINTHROP, MASSACHUSETTS, ASSIGNOR TO AMERICAN WIRE-MOLD COMPANY, OF HARTFORD, CONNECTICUT, A CORPORATION OF CONNECTICUT.

BRAIDING MACHINE.

1,413,773.

Specification of Letters Patent. Patented Apr. 25, 1922.

Application filed January 3, 1921. Serial No. 434,577.

To all whom it may concern:

Be it known that I, ANKER PETERSEN, a citizen of the United States of America, and resident of Winthrop, in the county of Suffolk and State of Massachusetts, have invented new and useful Improvements in Braiding Machines, of which the following is a specification.

This invention relates to circular braiding machines of that type in which a series of thread carriers are caused to travel in a generally circular path about a central point while a second series of carriers is revolved in the opposite direction, the threads from the two series intertwining at said central point to form a braid. The invention, while generally applicable to braiding machines having the characteristics above outlined, is herein illustrated as applied to a machine of the specific type disclosed in patent to Petersen, 1,331,672, Feb. 24, 1920, to which reference may be had for the detail construction and arrangement of the braiding elements and the devices for operating the same.

25 The present invention consists in the novel features of construction hereinafter described and particularly pointed out in the claims.

In the accompanying drawings wherein one embodiment of the invention is illustrated, only such parts of the braiding machine proper are shown as are necessary for an understanding of the novel features of this invention.

35 Fig. 1 is a side elevation of a braiding machine having the invention applied thereto;

Fig. 2 is a cross section to larger scale, on the line A—B of Fig. 1;

Fig. 3 is a cross section to large scale, on the line C—D of Fig. 1, and;

Fig. 4 is a fragmentary, detail elevation of a stop wheel employed in the device.

The circular frame 1 of the machine is supported upon legs 2. Mounted for rotation in the frame 1 is a support 3 upon which are arranged thread carriers 4 forming one of the two oppositely moving series of carriers. Threads 5 are indicated as extending from the thread carriers 4 to the braiding point. The series of thread carriers which move in the opposite direction, are not herein illustrated, being concealed by the frame 3.

The main drive shaft 7 has a fast pulley 8 thereon and a loose pulley 9, said shaft being supported at 10 in a bearing carried by a

depending bracket 11 secured to the frame member 1.

A beveled gear 12 is fast to the shaft 7 and serves to drive gears 13, 14 in opposite directions. The gears 13, 14 rotate the upper and lower thread carrier supports respectively in the usual manner.

A belt shifter fork 15 is supported upon a shaft 16 provided with an outstanding arm 17 adapted to be retained in adjusted position by means of a latch 18 which may be magnetically controlled. Secured to the frame 3, as by means of bolts 20 is a yoke member 19, said yoke member extending upwardly from the frame and being provided with a substantially horizontal portion 21 which bridges the machine and extends substantially diametrically across the same. Depending from the member 21 is an integral bracket 22 having secured adjacent its lower end a secondary bracket 23. Upon the latter is carried the braiding die 24. Such die may consist either of a solid bar over which the braid is formed or a ring or tube through a circular bore in which the braided material passes to the takeup drum hereinafter described.

A transverse shaft 25 is rotatable in bearings at 26, 27 and 28, carried by the bracket 22, the yoke 19, and an outstanding bracket 30 carried by the latter, respectively. A second shaft 31, substantially parallel to shaft 25, turns in bearings 32 and 33, said shaft having a pinion 34 meshing with a pinion 35 carried upon the outer extremity of shaft 25. The shaft 31 also has a beveled gear 36 meshing with the bevel gear 37 carried upon the upper end of a vertical shaft 38 rotatably supported in fixed bearings at 39, 40. Upon the lower end of the shaft 38 is fixed a worm wheel 41 engaging a worm 42 fast upon the main drive shaft 7. Thus through the connections just described the shaft 25 will be rotated simultaneously with the rotation of shaft 7.

Upon its left hand extremity, (Fig. 1) the shaft 25 is provided with a pinion 43 which meshes with an internal gear formed upon the inside of the takeup drum 44. The takeup drum 44 is fixed upon a short shaft 45 rotatable in bearings 46, carried by the bracket 22. Secured to the opposite end of the shaft 45 is a worm 47 (Fig. 2) meshing with a worm wheel 48 fast to a vertical shaft 49 mounted on pintle bearings at 50, 51

100

105

110

in a supporting frame 52 carried by the bracket 22. A worm 53 is fast upon the shaft 49.

54 is a bracket arm outstanding from the frame 52 and provided with a longitudinal slot 55. A stub shaft 56 is mounted to slide in the slot 55, and a nut 57 is provided whereby such shaft may be secured in adjusted position in said slot. A worm wheel 58 is mounted to turn freely on shaft 56, said wheel being adapted to mesh with the worm 53 and to be driven by the latter.

Secured on one face of the worm wheel 58 is a disc 59 of insulating material, such 15 for example as mica, hard rubber or the like. At one or more points in this disc is provided an opening or slot 60.

A resilient metallic arm 61 is secured at 62 to the frame 52, from which it is suitably insulated, and 63 is an electrical conductor which is electrically connected to the arm 61. The arm 61 is provided with a toe or contact element extending substantially at right angles to the main portion thereof, 25 such toe normally resting upon the surface of the insulating disc or plate 59. When, however, the slot or opening 60 is brought opposite such toe, the latter may move through such slot and into contact with the stop wheels 58 whereby to complete an electric circuit of which the machine frame 30 forms an element. An arm 64 of insulating material is pivoted at 65 to the wheel 58, and has a portion 66 which may be swung into 35 position to cover the slot 60 and to support the toe of the finger 61, whereby to prevent the same from entering the slot.

A spindle 67 is mounted to turn in substantially horizontal bearings at 68, 69, respectively, carried by upstanding bracket members 70, formed integrally with the yoke member 21, or if desired secured thereto in any desired manner. The left hand end of the spindle 67 projects beyond the bearing 45 68 and is adapted to have mounted thereon a spool 70 or other suitable support upon which the braided material may be wound.

At the right of the bearing 69, the shaft 67 is provided with a fixed flanged collar 71, 50 (Fig. 3). A second collar 72 is arranged to slide longitudinally upon the spindle 67 and between the collars 71, 72 is mounted to turn freely a sprocket wheel 73. Between the collar 72 and the sprocket wheel 73 is arranged 55 a friction washer 74 of felt or other suitable material. A coiled spring 75 surrounds the spindle 67, bearing at one end against the collar 72, and at its other end against an adjustable nut 76 which engages screw threads 77 upon the end of the spindle. By 60 means of the nut 76 the tension of the spring 75 may be varied and thereby the frictional pressure of the washer 74 against the sprocket 73 may be varied.

65 Passing over the sprocket 73 is a sprocket

chain 78 which engages a sprocket wheel 79 fixed upon a shaft 25 above described. The rotation of shaft 25 thus serves to rotate the sprocket wheel 73 and through the slip connection or friction clutch of which the 70 friction washer 74 forms an element, the spindle 67 is driven, but in a nonpositive manner. Secured upon the spindle 67 is a pinion 80 engaging a gear 81 mounted upon a shaft 82 turning in bearings in bracket 75 members 70. A pinion 83 upon the shaft 82 engages a gear 84 upon a transverse shaft 85 mounted in bearings at 86, 87 respectively. Such shaft has mounted thereon a traverse cam 88. The traverse cam 88 serves in a 80 well known manner to actuate a traverse guide 89 having spaced guide arms 90, between which may pass the material to be wound upon the spool.

The general arrangement of the parts is 85 such that the takeup drum 44 and winding spool 70 lie substantially above the braiding die 24.

In the operation of the machine, it being assumed that the drive belt is in engagement 90 with the fast pulley 8 and that the belt shifter member 15 is suitably latched in operative position, the gears 13 and 14 will be rotated in opposite directions and thereby the two series of thread carriers will be oppositely revolved whereby to intertwine their respective threads at the braiding point to form a braid in the usual manner. The present machine is primarily intended for the formation of a braided thread such as is employed in the sewing of shoes, such braided thread as it is formed passing on through the braiding die 24. The thread is then given one or more complete turns about the takeup drum 44; in most cases it will be 105 found necessary to pass the braided material several times about the periphery of the drum 44 in order to avoid slipping of the same relative thereto. From the drum 44 the braided material may pass between the 110 arms 90 of the traverse guide and is secured to the spool 70 upon which it is to be wound.

In starting the machine the insulating member 64 will be swung to a position such that it covers the slot 60, the finger 61 being 115 sprung outwardly so that its toe rests upon the edge of the member 66, thus breaking the contact through the wheel 58. The machine now continues to form braided material which is drawn off under proper tension by 120 the takeup drum 44 and wound upon the spool 70. The friction clutch drive between the shaft 25 and the spindle 67 permits the spool 70 to wind the material as fast as formed, while the friction clutch arrangement 125 serves to compensate for variations in the winding diameter of the mass of material upon the spool. In this connection it may be stated that the normal speed of rotation of sprocket wheel 73 is such as to prop- 130

erly drive the spindle 67 at the highest speed necessary for proper winding of the braided material.

As the traverse guide 89 is driven directly from the spindle 67, it is clear that the traverse of the material along the spool, will always be in proportion to the speed of rotation of the latter. As the takeup drum 44 rotates, the contact wheel 58 will be rotated at very slow speed through the worm gearing described, and as this wheel turns in a clock-wise direction as seen in Fig. 1, the friction between the finger 61 and the edge of the member 66 will gradually swing the arm 64 away from the slot 60 into substantially the position shown in Fig. 4.

The machine continues thus to operate until the wheel 58 has made a complete rotation or until a slot 60 has been brought beneath the toe of finger 61. Such toe thereupon slips into the slot and serves to make electric contact with the metallic wheel 58. This serves to complete an electric circuit which may in any well known manner serve to indicate to the operator that the spool 70 has received the proper amount of braided material.

Such indication may take the form of an audible signal such for example as the ringing of a bell or a visual indication by causing a lamp to glow or a finger to swing over a dial, or if desired such circuit may operate automatically to stop the machine by energizing a magnetic releasing device of a common and well known type such as indicated generally at 18. In the latter case, belt shifter 15 would be moved to carry the belt to the loose pulley, thus stopping the machine and thereby notifying the operator that the spool 70 has received its proper supply of material and should be doffed for replacement by an empty spool. For winding spools of different size, or for winding different quantities of material upon the spool, it is merely necessary to provide wheels 58 of different diameters which may be interchangeably mounted upon the shaft 56. The sliding of the shaft 56 along the slot 55 permits such interchange. By selecting a wheel 58 of the proper diameter, it is thus possible to cause the machine to indicate the winding of any desired quantity of material upon the spool.

It is understood that independent mechanisms generally similar in function to some of those above described, have heretofore been employed in the textile arts. It is believed that applicant is the first to combine in a unitary device and in the simple and compact form herein disclosed, braiding instrumentalities and a series of mechanisms which serve to properly take up the braided material, to wind the same upon a suitable spool or support, and to indicate automatically the proper point for stopping the ma-

chine after the braiding of a predetermined length of material. Applicant has combined with the braiding machine proper suitable supporting means whereby all the mechanisms necessary are combined to form a single unit, requiring no independent supports or auxiliary mechanisms, while at the same time making it possible for a single operator to attend to a very large number of machines.

While the mechanism described is regarded as a preferred mechanical embodiment of the invention it is to be understood that various changes and rearrangements of parts might well be made without departing from the spirit of the invention.

Having thus described one form of the invention together with the mode of operation thereof, what I claim and desire to secure by Letters Patent of the United States is:

1. A circular braiding machine having a supporting member extending diametrically across and above the same, a braiding die carried thereby at a point substantially above the center of the machine, a takeup drum carried by said member and disposed substantially above the braiding die, and a winding mechanism mounted upon said supporting member substantially directly above said drum, said mechanism comprising an automatically acting traverse guide.

2. A circular braiding machine having a supporting member upstanding therefrom, a shaft rotatable in bearings in said supporting member, a pinion fast to said shaft, a takeup drum arranged substantially above the braiding point and mounted to turn upon a stub shaft fixed in said supporting member, said drum having an internal gear meshing with said pinion, and connections for rotating said first named shaft.

3. A braiding machine having a main drive shaft, a yoke member extending above and bridging the machine, a takeup drum carried by said yoke member, a winding spindle rotatably mounted upon said member, a transverse shaft for driving said takeup drum, connections, including a friction clutch, between said shaft and spindle, and means interposed between said drive shaft and the transverse shaft, whereby the latter is driven.

4. A braiding machine having a series of rotating braiding carriers, a yoke member extending above and bridging the machine, a take-up drum carried by said yoke member, a winding spindle rotatably mounted upon said member, a reciprocable traverse guide associated with said spindle and driven thereby, a shaft for driving the take-up drum, connections between said shaft and spindle for driving the latter, and means for rotating said shaft in consonance with rotation of the braiding carriers.

5. A braiding machine having a takeup drum, a shaft for rotating the same, an electrical contact wheel actuated through positive connections to said shaft, an insulating plate having a slot therein, secured to said wheel, and a resiliently supported contact member normally engaging said disc but movable into said slot for completing an electrical circuit through the wheel.
- 10 6. A braiding machine having a main drive shaft, a support, a shaft rotatable in said support, a takeup drum fixed to said shaft, a rotatable contact member provided with an isolated contact surface, a resilient contact finger engageable with said surface whereby to complete an electrical circuit, means interposed between said takeup shaft and said rotatable member for turning the latter, and connections from the main drive shaft for rotating the takeup shaft.
- 15 7. A braiding machine having a takeup drum, a contact wheel, means for rotating said wheel in consonance with said drum, an insulating plate secured to one face of the wheel, said plate having an opening therethrough, a contact finger movable through said opening for engaging said wheel and movable means for guarding said opening.
- 20 8. In combination in a braiding machine having a takeup wheel, a contact wheel having an insulating disc secured to one face of said wheel, said disc having an opening therethrough, a sector of insulating material pivoted to said plate and swingable over said opening, and a resilient contact member having an element movable through said opening when unobstructed, whereby to make electrical contact with said wheel.
- 25 9. In combination in a braiding machine having a takeup drum, a rotatable contact wheel, means for rotating said drum and wheel in consonance, means engageable with said wheel at predetermined times in the rotation thereof whereby to complete an electrical circuit, and means movable with
- 50 the wheel for temporarily preventing such engagement.
- 55 10. A braiding machine comprising a takeup drum, a contact wheel rotatable in consonance with said drum, a member provided with a contact toe engageable with said wheel, whereby to complete an electrical circuit, and a part carried by said wheel and movable into position to prevent engagement of said toe with the wheel, said part having an element engageable with said member whereby to restrain said part against free rotation with the wheel.
- 60 11. In combination in a circular braiding machine, a takeup drum, and means for indicating a predetermined number of rotations of the same, said means comprising an interchangeable electrical contact wheel.
- 65 12. In combination in a braiding machine, a yoke member bridging the same, a takeup drum carried thereby, a shaft driven in consonance with said drum, a worm carried by said shaft, a slotted bracket, and a support adjustable along the slot in said bracket, said support being constructed and arranged selectively to carry worm wheels of different diameters for driving engagement with said worm.
- 70 13. A circular braiding machine comprising a main drive shaft, a yoke frame bridging said machine, a braiding die carried by said frame, a take up drum rotatably supported in said frame above said die, a winding spindle above said drum and mounted for rotation in said frame, an electrical contact wheel rotatably supported upon the frame, positive drive connections between said main drive shaft and the takeup drum and contact wheel respectively, and friction drive means between said shaft and said spindle.
